UNITED STATES PATENT OFFICE.

JOHN M. ALDERFER, OF AKRON, OHIO.

DESIGN FOR AN ELASTIC VEHICLE-TIRE.

57,566.

Specification for Design. Patented Apr. 26, 1921.

Application filed September 18, 1919. Serial No. 324,704. Term of patent 14 years.

To all whom it may concern:

Be it known that I, JOHN M. ALDERFER, a citizen of the United States, residing at Akron, in the county of Summit and State of Ohio, have invented a new, original, and ornamental Design for Elastic Vehicle-Tires, of which the following is a specification, reference being had to the drawing forming a part thereof.

In the drawings, Figure 1 is a perspective

view of an elastic vehicle tire showing my new design, and,

Fig. 2 is a perspective view of a portion of a tire partly in cross section illustrating more in detail my new design.

I claim:

The ornamental design for an elastic vehicle tire as shown.

JOHN M. ALDERFER.
